Primary Examiner — Selina Sikder(74) *Attorney, Agent, or Firm* — Dinsmore & Shohl LLP(57) **CLAIM**

The ornamental design for an adjustable bed remote control, as shown and described.

DESCRIPTION

FIG. 1 is a perspective illustration of the front of an adjustable bed remote control in accordance with the present invention;

FIG. 2 is a top plan view thereof;

FIG. 3 is a bottom plan view thereof;

FIG. 4 is an end view thereof;

FIG. 5 is another end view thereof; and,

FIG. 6 is a side view thereof, the opposing side being a mirror image thereof.

The broken lines shown in the Figures are for environmental purposes only and form no part of the claimed design.

Surface shading lines are provided to show surface contour and do not represent surface ornamentation.
